UNITED STATES PATENT OFFICE

145,406

DESIGN FOR A SLICING MACHINE

Paul H. Meyer, La Porte, Ind., assignor to U. S.
Slicing Machine Company, La Porte, Ind., a
corporation of Indiana

Application March 24, 1945, Serial No. 118,679

Term of patent 14 years

(Cl. D55—1)

To all whom it may concern:

Be it known that I, Paul H. Meyer, a citizen of the United States, residing at La Porte, La Porte County, Indiana, have invented a new, original, and ornamental Design for a Slicing Machine, of which the following is a specification, reference being had to the accompanying drawings, forming a part thereof.

Fig. 1 is a perspective view showing the front and left-hand side of a slicing machine showing my new design;

Fig. 2 is a perspective view showing the right-hand side of the machine with the carriage at the forward end of its stroke;

Fig. 3 is a perspective view showing the right side and far end of the machine, the carriage being shown in a position midway of its stroke;

Fig. 4 is a perspective view showing the front of the machine; and

Fig. 5 is a perspective view showing the right-hand side of the machine.

I claim:

The ornamental design for a slicing machine, as shown.

PAUL H. MEYER.
